UNITED STATES PATENT OFFICE.

ISAAC HARRIS, OF DETROIT, MICHIGAN.

TELLTALE SPARK-PLUG.

1,343,626.

Specification of Letters Patent. Patented June 15, 1920.

Application filed May 21, 1919. Serial No. 298,659.

To all whom it may concern:

Be it known that I, ISAAC HARRIS, a citizen of the United States of America, residing at Detroit, in the county of Wayne and State of Michigan, have invented new and useful Improvements in Telltale Spark-Plugs, of which the following is a specification.

The object of the invention is to provide a spark plug of simple and efficient construction wherein the proper functioning of the terminals of electrodes is apparent upon inspection without removing the plug or applying any of those tests which are now in common use in this connection, and wherein the tension due to a spark gap in the sparking circuit may be modified at the will of the operator to suit the conditions under which the plug is being employed.

With these and related objects in view the invention consists in a construction, combination and relation of parts herein-after fully explained, it being understood that changes in form, proportion and details may be resorted to, within the scope of the claim without departing from the principles involved.

Figure 1 is a side view of a spark plug embodying the invention.

Fig. 2 is a longitudinal sectional view of the same.

Fig. 3 is a transverse sectional view on the plane indicated by the line 3-3 of Fig. 1.

Fig. 4 is a sectional view on the plane indicated on the line 4-4 of Fig. 2.

The porcelain body portion 10 of the plug is seated within the bowl nut 11 upon a suitable gasket 12 where it is held by means of a gland 13 threaded into the bowl nut and bearing upon a shoulder 14. Said bowl nut is of polygonal contour to form a wrench seat whereby the threaded sleeve portion 15 thereof may be engaged with the motor-head indicated at 16.

The terminals or electrodes 17 and 18 are arranged in the ordinary way common to jump spark plugs with the latter which is insulated by the porcelain body portion

and extends axially therethrough provided with a collar 19 which is spaced from the end wall of the cavity 20 by means of a washer 21 which serves to prevent the passage of gases from the interior of the motor cylinder to the bore of the porcelain body. Below the collar 19 the electrode 18 is preferably provided with a polygonal wrench seat 22.

This electrode 18 is divided to form elements 23 and 24 which are separated at their adjacent extremities to form a spark gap located within a transverse recess 25 in the porcelain body of the plug, metallic reinforcing elements 26 being embedded in the latter adjacent to the recess and the upper portion of said body inclosing the recessed zone thereof being surrounded by a glass or similar transparent protective shield 27 through the wall of which the interior of the recess 25 and the spark gap may be viewed from the side of the plug without removal of the latter from the motor.

The upper extremity of the lower electrode member 23 is threaded and fitted with a nut 28 and the lower extremity of the upper member of said electrode is correspondingly fitted with a nut 29 by the adjustment of which the extent of the spark gap may be modified while the terminal 30 of the electrical connection 31 is engaged by a thumb nut 32 threaded upon the upper end of the upper electrode member and is thereby held in contact with a cap plate 33 which bears upon the upper end of the porcelain body of the plug.

Obviously, when the spark plug is properly functioning there is at each stroke of the motor mechanism a spark or flash at the spark gap represented by the adjacent extremities of the members of the positive electrode 18, and the absence of such a spark is an indication to the operator that the connections are at fault and require attention, and the extent of the gap obviously determines the increase in tension of the current at the sparking terminals within the engine cylinder and may be varied by the adjust-

ing means above described to secure the desired results and the conditions as they may be found to exist in practice.

Claim:—

- 5 A spark plug having an insulating body provided at an intermediate point with a transverse terminally open recess, reinforcing elements embedded in the body adjacent to said recess, a transparent sleeve em-

bracing the body in the zone of and closing 10 the extremities of said recess and a sectional electrode having its members terminally separated to form a spark gap within said recess.

In testimony whereof I affix my signature. 15
ture.

ISAAC HARRIS.
